UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF WISCONSIN

AUTOMOBILE IGNITION LOCK

Application filed June 3, 1927. Serial No. 196,279.

This invention relates to certain new and useful improvements in automobile locks and has as an object the provision of means whereby the withdrawal of the locking key is essential to the stopping of a motor to thus preclude the negligent or absent-minded leaving of the key in the lock.

Another object of this invention resides in the provision of an improved circuit closer 10 and lock for operating the same having means whereby, after the initial closing of the circuit, no amount of rotation of the key will open the circuit, but withdrawal of the key from the lock instantly moves the circuit closer to open position whereby careless leaving of the key in the lock to thus invite the theft of the car by persons so inclined is prevented.

A further object of this invention resides 20 in the provision of an improved lock of the character described having an arcuate tail or cam portion for actuating the movable member of a circuit closer and an auxiliary member concentrically of the lock and the cam or 25 tail and key urged to engage the movable switch member after the same has been moved to a circuit closing position and prevent the movement of said member to circuit breaking position until the key has been withdrawn.

And a still further object of this invention resides in the provision of an improved locking device for a vehicle ignition circuit adapted to be associated with the conventional ignition coil and operable from the dash and having a direct connection between the lock plug and the movable switch member.

With the above and other objects in view 40 which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have 50 illustrated one complete example of the phys-

ical embodiment of my invention constructed according to the best mode I have so far devised for the practical application of the principles thereof, and in which:

Figure 1 is a view through a portion of 55 an automotive vehicle instrument mounting panel or board illustrating the application thereto of my improved device, parts of which are in section and parts of which are in elevation;

Figure 2 is a view, partly in section and partly in elevation, taken through Figure 1 on the plane of the line 2-2;

Figure 3 is an enlarged detail view, partly 60 in section and partly in elevation, taken 65 through Figure 2 on the plane of the line 3-3 and illustrating the lock assembly proper;

Figure 4 is an enlarged fragmentary view 70 of the circuit closer taken through Figure 1 on the plane of the line 4-4, parts thereof being in section and parts in elevation;

Figure 5 is a fragmentary view similar to 75 Figure 4 illustrating the circuit closer as in one position, and

Figure 6 is an enlarged fragmentary view, partly in section and partly in elevation, taken through Figure 5 on the plane of the line 6-6.

Referring now more particularly to the accompanying drawings in which like numerals 80 designate like parts throughout the several views, 5 designates the core and 6 the ignition coil wound therearound of a conventional automotive vehicle ignition circuit, the 85 coil and core being enclosed within a housing formed of two substantially complementary caps or covers 7 and 8 having their marginal portions flanged laterally, as at 9, and riveted or otherwise secured to the core 5, as at 10. The coil assembly is mounted from the rear of the dash or instrument panel 11 of the automotive vehicle by a bracket structure 12 the lower end of which terminates in a shelf structure 12' to which the coil housing is secured by the lowermost rivets 10.

The cover or cap 8 at the opposite side from the panel 11 has an aperture 13 therein through which an insulating head 14 projects to the interior of the housing, the head 14 100

being fixed to the housing by screws or other means 15 and providing a terminal for a high tension cable 16 leading from one side of the high tension winding, not shown, of the coil to the distributor, not shown, of the ignition circuit in which the coil is incorporated.

The cap 7 is cut away to provide an elongated opening 17 which is closed by a panel of insulating material 18 suitably riveted thereto, as at 19, and fixed to the panel 18 at one side of an opening 20 therein is a pair of terminals 21 and 22, the terminal 21 being connected with one side of the low tension winding, not shown, of the ignition coil by a conductor 23 and the terminal 22 being connected with the other side of the low tension winding by a lead 24 and with one side of the conventional breaker box, not shown, by a conductor 25, the ignition circuit being normally broken at the terminal 21 in the manner to be described. As is customary in circuits of this type, the other side of the breaker box is suitably connected with the positive side of the source of current, not shown, the negative side of which is frequently connected through an ammeter, not shown, and then with the terminal 21, the conductor 26 from the ammeter being electrically connected, as at 27, with a terminal 28 fixed to the insulation 18 and having an end 29 extended into the casing 7 to provide a pivotal mounting for a movable switch member 30, to be later described.

The movable switch member 30 consists of a strip of resilient contacting material having one end reduced to form a teat 31 which has a rocking or swivel connection with the terminal end 29 by being projected through an aperture 32 therein. The free end 33 of the member 30 is arranged to electrically engage the terminal 21 which is a post projected into the casing 7, a strip of insulating material 34 being riveted medially to the member 30 at its under side in register with the aperture 20. One end 35 of a contractile spring 36 is connected with the movable switch member by a clip 37 and the other end 38 of the spring is connected to an attaching member 39 fixed to the panel 18, the spring 36 passing through an aperture 40 in the panel and exerting a tension on the movable switch member so that the teat 31 is retained in the aperture 32, the other end 33 thereof is yieldably urged out of engagement with the contact 21 and the switch is normally yieldably urged toward the panel 18, for the reason later described.

Secured in the aperture 20 of the insulation 18 is a guide sleeve or bushing 41 in which the inner end portion 42 of a locking barrel mounting head 43 is guided, the locking barrel mounting head projecting through the panel 11 and an escutcheon plate 44 of conventional construction and being secured thereto by the usual jam nut 45, sleeve 41

serving to align the locking barrel mounting head during installation. The locking barrel mounting head has an outer bore 45 and an inner bore 46 concentric with the outer bore and of smaller diameter and communicating with the interior of the ignition coil housing and a cylinder or plug 47 is rotatable in the bore 45 and has a reduced inner end 48 projecting into the coil housing through the reduced bore 46. The cylinder or plug 47 is provided with lock tumblers 49 of conventional construction and movable into a longitudinal slot 50 communicating with the bore 45 of the locking barrel mounting head, the tumblers being retractile by a proper key 51 to free the plug for rotation, the plug being secured against inward movement by the shoulder formed at its juncture with its reduced end 48 abutting the shoulder at the juncture of the bores 45 and 46 and against outward movement by the cap 52 secured over the outer end of the locking barrel mounting head and extending behind a shoulder 53 formed at the extreme outer end of the plug. The inner reduced end portion 48 of the locking plug or cylinder is bored, as at 54, and the portion thereof extended beyond the panel 18 is cut away to form an arcuate tail or cam 55 disposed under the insulation 34 of the movable switch member and against which the movable switch member is held by the spring 36 so that rotation of the plug by the key 51 in either direction causes the tail or cam 55 to move the switch element in the manner illustrated in Figure 5 to engage its free end with the contact 21.

To prevent disengagement of the movable switch member and contact 21 except upon the locking of the plug by the withdrawal of the key 50, a pin or plunger 56 is slidably mounted in the plug inner end by a bushing or sleeve 57 threaded in the bore 54 at the inner end of the cam 55 and the pin or plunger is normally retracted to the position illustrated in Figure 3 by an expansible spring 58 confined between the bushing 57 and a head 59 on the inner end of the plunger and guided in the bore 54. The head 59 normally abuts the shoulder formed at the inner end of the bore 54 and the key-way slot 60 of the plug or cylinder communicates with bore 54 so that upon insertion of the key 51 its inner end strikes the head of the plunger moving it outwardly of the bore 54 against its spring. Outward movement of the pin 56 causes a similar movement of the movable switch member which is permitted by its swivel connection with the terminal 29 and as the plug is rotated by the key 51 the cam or tail 55 moves the same into electrical engagement with the contact 21. As the medial portion of the movable switch member is moved out of alignment with the plunger 56, the spring 36 pulls the same toward the panel 18 to its

position to one side of the pin 56 as illustrated in Figures 5 and 6.

Thus it will be seen that after its initial operation by rotation of the plug by the key, 5 the switch is held closed by the pin 56 which is secured against retraction by the key 55 remaining in the lock, and no amount of rotation of the sleeve or plug 47 by the key will effect the breaking of the circuit between 10 member 30 and contact 21. Before the circuit can be interrupted, it is essential that the key 51 be withdrawn permitting the spring 58 to retract the plunger 56 out of the path of the member 34 when its spring 36 instantly pulls it to its position illustrated in 15 Figure 4.

The member 30 engages the terminal 21 prior to the completion of its movement out of alignment with the pin 56 so that the 20 member 30 is sprung slightly when the lock cylinder comes to rest and the pin engages the side of the member 30. The spring 36 is of course strong enough to overcome the 25 tendency of friction between the member 30 and the terminal 21 to retard the movement of the member 30 toward the panel. This springing of the member 30 insures a good 30 electrical engagement between it and the terminal 21 and further, should the key be turned far enough to close the circuit, but not far enough to permit the member 30 to be pulled off the end of the pin 56 and into 35 engagement with its side as illustrated in Figures 5 and 6, the lock cylinder will be rotated back by the spring 36 when the turning pressure on the key 51 is released.

From the foregoing description taken in connection with the accompanying drawings, 40 it will be readily apparent to those skilled in the art to which an invention of the character described appertains that I provide a novel and improved lock structure which will necessitate the withdrawal of the key from the lock to effect the interruption of the 45 circuit and further that I provide an improved lock structure capable of production at a cost no greater than that of the conventional lock now in general use.

What I claim as my invention is:

50 1. A locking device of the character described, comprising in combination with a movable member, a second member adapted upon rotation by a proper key inserted therein to move the first member in one direction, means automatically moving the movable member in another direction to a predetermined position after a predetermined degree of movement in the first direction, and a third member for retaining the first member 55 in said predetermined position and adapted to be moved by the insertion of a proper key in said second member.

2. A locking device of the character described, comprising in combination with a 60 movable member, a key actuated rotatable

member adapted upon rotation to move the first member in one direction, means for automatically moving said first member in another direction to a predetermined position after a predetermined degree of movement of the first member in said first direction, and means actuated by the insertion of a proper key in the second member to secure the first member in said predetermined position, said means retaining the first member in said position until the key is withdrawn. 70

3. A locking device of the character described, comprising in combination with a movable member, a key actuated rotatable member adapted upon actuation to move the first member in one direction, means for automatically moving said first member in another direction to a predetermined position after a predetermined degree of movement of the first member in said first direction, means actuated by the insertion of a proper key in the second member to secure the first member in said predetermined position, said means retaining the first member in said position as long as the key remains in the second member, and means moving the first means to inoperative position upon withdrawal of the key to permit the movement of the first member from its first-mentioned position. 85

4. The combination with a movable member, of a rotatable key actuated member having a key receiving slot in its outer end and a bore in its inner end, a member on the inner end of the second member eccentric with respect to its bore and adapted to move the first member in one direction, means for moving the first member in another direction to a predetermined position after a predetermined degree of movement in said first direction, and means mounted in the bore of the second member and actuated by the insertion of a key in the slot thereof to engage behind the first member when moved to said predetermined position to secure the same in such position. 90

5. The combination with a movable member, of a rotatable key actuated member having a key receiving slot in its outer end and a bore in its inner end, a member on the inner end of the second member eccentric with respect to its bore and adapted upon rotation of the key actuated member to move the first member in one direction, means for

moving the first member in another direction to a predetermined position after a predetermined degree of movement in said first direction, means mounted in the bore of the second member and actuated by the insertion of a key in its slot to engage behind the first member when moved to said predetermined position and secure the same in such position, and means operable upon the withdrawal of the key from the second member 115 to retract the means mounted in the second 120

125 member. 130

member bore out of engagement with the first member to permit its movement from said predetermined position.

6. In a locking device of the character described, the combination with a mounting panel, a plate spaced from the panel and a movable member supported therefrom, of locking means including a locking barrel mounting head fixed to the panel and registering with an aperture in said plate, a pilot sleeve fitted within the plate aperture and receiving the inner end of the locking barrel mounting head, a key actuated barrel mounted in the locking barrel mounting head, and cooperating means between the key actuated barrel and the movable member whereby rotation of the barrel actuates said member.

7. In a locking device of the character described, the combination with a mounting panel, a plate spaced from the panel and a movable member supported from the plate, of locking means including a locking barrel mounting head fixed to the panel and registering with an aperture in said plate, a pilot sleeve fitted within the plate aperture and receiving the inner end of the locking barrel mounting head, a key actuated barrel mounted in the locking barrel mounting head, cooperating means between the key actuated barrel and the movable member whereby rotation of the barrel actuates said member, and means securing the movable member in one position while the key remains in the key actuated barrel.

8. The combination with a member mounted for movement out of either of two planes, of a rotatable key actuated member having a key receiving slot, means actuated by the key actuated member and engageable with the first member to move the same out of one plane as the key actuated member is rotated, means normally retracted within said key actuated member and movable outwardly thereof by the insertion of a proper key in the key actuated member to move the first member out of the other plane, and means for retracting said first member into said second plane after the first member has been moved a predetermined degree relative to said normally retracted means by rotation of the key actuated member.

9. The combination with a member mounted for movement in either of two planes, of a rotatable key actuated member having a key receiving slot, an eccentric member extended from the inner end of the key actuated member and engageable with the first member to move the same in one plane as the key actuated member is rotated, means normally retracted within said key actuated member and movable outwardly thereof by the insertion of a proper key in the key actuated member to move the first member in another plane, and means for moving said first member over

said normally retracted means after the same has been moved a predetermined degree by rotation of the key actuated member.

10. In a lock of the character described, a movable member, means mounting said member for movement in either of two planes, a rotatable key actuated member having a key receiving slot, means on the inner end of said member and adapted to move the movable member in one plane as the key actuated member is rotated by a proper key, means operable upon the insertion of a proper key in the key actuated member to move the first member in another plane, and means moving the first member over said last means as said member is moved to one position in the first-mentioned plane by rotation of the key actuated member.

11. In a device of the character described, a resilient member, means pivotally mounting one end of the resilient member, a stop against which the other end of the resilient member is engageable, a key actuated member, a connection between the key actuated member and the resilient member whereby rotation of the key actuated member by a proper key moves the resilient member to engagement with the stop, a member projectable from the key actuated member by the insertion of a proper key, and means for engaging the resilient member with one side of the projectable member after the resilient member has been flexed by engagement with the stop to retain the resilient member in engagement with the stop independent of the key actuated member.

12. In a device of the character described, a resilient member, means pivotally mounting one end of the resilient member, a stop against which the other end of the resilient member is engageable, a key actuated member, a connection between the key actuated member and the resilient member whereby rotation of the key actuated member by a proper key moves the resilient member to engagement with the stop, a member projectable from the key actuated member by the insertion of a proper key, and means for engaging the resilient member with one side of the projectable member after the resilient member has been flexed by engagement with the stop to retain the resilient member in engagement with the stop independent of the key actuated member, said means normally urging the free end of the resilient member from the stop.

13. In a device of the character described, a resilient member, means pivotally mounting one end of the resilient member, a stop against which the other end of the resilient member is engageable, a key actuated member, a connection between the key actuated member and the resilient member whereby rotation of the key actuated member by a proper key moves the resilient member to engagement with the stop, a member projectable from the key actuated member by the insertion of a proper

- key, and means for engaging the resilient member with one side of the projectable member after the resilient member has been flexed by engagement with the stop to retain the resilient member in engagement with the stop independent of the key actuated member, said means normally urging the free end of said resilient member from said stop, and means for withdrawing the projectable member from engagement with the resilient member when the key actuated member is moved to one position and the key retracted therefrom.
14. A locking device of the character described, comprising in combination with a member movable to and from an operative position, a key receiving member adapted upon rotation by a proper key inserted therein to move the movable member toward operative position, a stop adapted to be actuated to operative position by the insertion of a key in the key receiving member, and means for automatically engaging the movable member with the stop to hold the movable member in operative position irrespective of the position of said key receiving member, until the key is withdrawn.
15. In a device of the character described, the combination with a member movable to and from an operative position, of a key receiving member adapted upon rotation by a proper key inserted therein to move the movable member toward operative position, a stop normally substantially retracted within the key receiving member and projectable therefrom upon the insertion of a proper key, and means for engaging the movable member with the stop so as to hold the movable member in operative position.
16. In a device of the character described, the combination with a member movable to and from an operative position, of a key receiving member adapted upon rotation by a proper key inserted therein to move the movable member toward operative position, a stop normally substantially retracted within the key receiving member and projectable therefrom upon the insertion of the key, and means for engaging the movable member with the stop so as to hold the movable member in operative position, said stop being substantially co-axial with the key receiving member whereby the stop holds the movable member in its operative position irrespective of rotation of the key receiving member subsequent to the movable member reaching its operative position.
17. In a device of the character described, the combination with a member movable to and from an operative position, of means for yieldably urging the movable member toward inoperative position, a key receiving member rotatable upon the insertion of a proper key, a stop projectable from the key receiving member upon the insertion of a key, a cam carried by the key receiving member and holding the movable member against the action of its yieldable urging means in alignment with the stop whereby the movable member is moved in a direction transversely to its movement to and from operative position by the projection of the stop and against the action of its yieldable urging means, said cam upon rotation of the key receiving member moving the movable member toward its operative position and out of alignment with the stop whereby the yieldable urging means moves the movable member in back of the stop so that the stop holds the movable member in its operative position irrespective of the position of rotation of the key receiving member.
18. In a lock switch of the character described, a stationary switch terminal, a switch member movable to and from engagement with the stationary switch terminal, means yieldably urging the switch member away from the stationary terminal, a rotatably mounted key receiving member adapted upon rotation by a proper key inserted therein to move the switch member toward the stationary terminal, and a stop projected from the key receiving member upon the insertion of the key for holding the switch member in engagement with the stationary terminal irrespective of the position of rotation of the key receiving member subsequent to the engagement of the switch member with the stationary terminal.
19. In a lock switch device of the character described, a member pivotally mounted for movement to and from an operative position, a key receiving member adapted upon rotation by a proper key inserted therein to move the movable member toward its operative position, a stop projectable from the key receiving member upon the insertion of the key and engaging the movable member to move the same in a direction transversely of its direction of movement to and from operative position, and means yieldably urging the movable member away from its operative position and toward the key receiving member whereby the movable member is automatically engaged behind the stop upon a predetermined degree of movement toward operative position by the rotation of the key receiving member.
20. In a device of the character described, the combination with a member pivotally mounted for movement to and from an operative position, of a key receiving member adapted upon rotation imparted thereto by a proper key inserted therein to move the movable member toward operative position, a stop for holding the movable member in operative position, and means yieldably urging the movable member to active engagement with the stop and away from its operative position.
21. In a device of the character described,

the combination with a movable member, of a key receiving member adapted upon rotation by a proper key inserted therein to move the movable member toward an operative position, a stop projectable from the key receiving member by the insertion of the key for holding the movable member in its operative position, and means yieldably urging the movable member away from its operative position and into active engagement with the stop whereby the movable member is automatically engaged with the stop upon rotation of the key receiving member and is automatically moved out of its operative position upon the withdrawal of the key.

22. In a device of the character described, and in combination with a member adapted to be moved to and from a predetermined position, a lock cylinder adapted upon rotation by a proper key inserted therein to move the movable member toward said predetermined position, a stop normally substantially retracted within the lock cylinder and projectable axially from its inner end by the insertion of the key, and means for automatically engaging the movable member behind the stop as the lock cylinder is turned to move the movable member toward said predetermined position whereby the stop holds the movable member in said predetermined position irrespective of subsequent rotation of the lock cylinder and until withdrawal of the key.

In testimony whereof I hereunto affix my signature.

EDWARD N. JACOBI.
